ABSTRACT: A wire dispensing mechanism in combination with a coil winding machine for feeding wire in the manufacture of coiled lamp filaments in which a spool of wire is carried by a reciprocating carriage. The carriage reciprocates perpendicular to the spool axis in timed sequence with the coil winding operation. The axis of the spool is further continuously rotated at a fixed speed about its midpoint in a plane perpendicular to the direction of reciprocation while also continuously rotating about its axis as the wire is pulled therefrom.

WIRE FEEDING MECHANISM

BACKGROUND OF THE INVENTION

In the manufacture of coiled filaments for a variety of types of lamps it is necessary that filament wire be continuously fed to what is known in the art as a coil winding machine. The operation of a coil winding machine generally involves the gripping of the cut end of the filament wire as it projects from the coil winding head by a reciprocal tail stock. The tail stock normally carries adjacent the wire gripping jaws what is known in the trade as a disappearing mandrel. As the mandrel and jaws move away from the coil winding head the coil winding head forms the coil about the mandrel. When the coil is formed the tail stock moves rapidly away from the coiling head to produce two coil legs and stops abruptly. This operation calls for the rapid starting and stopping of the motion of the tail stock as well as an intermittent rotation by the coil winding head which induces a great amount of torque into the remaining wire coming from the wire holding spool. This rapid starting and stopping as well as the turning of the spool imposes much stress and strain to the wire and in fact on many occasions will cause the wire to break due to the inertial effects acting on the wire. It has been a practice in the past, in order to avoid some of these effects, to rewind the wire to be used in the filament forming operation from shipping spools which hold approximately 9,000 meters of wire to smaller bobbin spools which hold approximately 300 meters of wire. This respooling of the wire also induces characteristics into the wire which are different from those which the wire originally evidences on the shipping spool. As presently operated with the 300 meter spools, the machine must be shut down and the bobbin spools changed twice during an 8-hour shift. If wire could be wound directly into filament coils from a shipping spool carrying 9,000 meters of wire it would be necessary to change the wire carrying spools only once in every 15 8-hour shifts.

SUMMARY OF THE INVENTION

This invention relates to wire dispensing mechanisms for coil winding machines and more particularly to a reciprocating continuously rotating wire dispensing mechanism for use in conjunction with coil filament winding machines.

An object of the present invention is to provide a wire dispensing mechanism for use in conjunction with coil winding machines which substantially reduces the tow torque induced into the wire during the filament winding operation.

Another object of the present invention is to provide a wire feed mechanism for use in conjunction with coil winding machines in which the back lash, stress and strain normally induced into the wire are substantially eliminated.

A further object of the present invention is the provision of a wire dispensing mechanism for use in conjunction with a coil winding machine in which wire is continuously being pulled from the supply spool and the supply spool is continuously rotating even when the coil winding head is motionless.

A still further object of the present invention is to provide a wire dispensing mechanism for use in conjunction with a coil winding machine in which the supply spool of wire traverses substantially the same longitudinal path as that traversed by the mandrel of the machine during the winding of the coil filament.

The foregoing objects, and others, are accomplished in accordance with the present invention by providing in combination with a coil winding machine which continuously winds filament coils about a reciprocable mandrel by means of a rotating coiling head mechanism; a wire dispensing mechanism which comprises a carriage mounted for reciprocal motion on a base and having a pair of upright support members which support a rotatable yoke mounted therebetween. A first drive means is also mounted on the carriage and connected for imparting continuous rotary motion to the yoke which in turn carries a wire containing spool for rotation about an axis perpendicular to the axis of rotation of

the yoke. Second drive means are connected to the carriage for imparting reciprocal motion to the carriage in a timed relationship to the linear motion of the tail stock mechanism of the coiling machine. The continuously rotating yoke imparts a counterclockwise torque to the wire being continuously drawn from the rotating spool and this counterclockwise torque is removed from the wire when the coiling head winds the filament on the mandrel. The constantly reciprocating carriage insures that wire is continuously drawn from the rotating spool even while the coiling head is stationary and hence not pulling wire from the spool by influence of its motion.

BRIEF DESCRIPTION OF THE DRAWING

The foregoing objects, and others, along with many of the attendant advantages of the present invention will become more readily apparent and better understood as the following detailed description is considered in connection with the accompanying drawings in which:

FIG. 1 is a side elevational view of a coil winding machine and the wire dispensing mechanism of the present invention.

FIG. 2 is an isometric view of the wire dispensing mechanism of the present invention.

FIG. 3 is a side elevational view of the cam mechanism of FIG. 1.

DESCRIPTION OF THE PREFERRED EMBODIMENT

Referring now in detail to the drawings, wherein like reference characters represent like parts throughout the several views, there is shown on the right-hand side of FIG. 1 a typical conventional coil winding machine which consists essentially of a driven lathe head assembly generally designated 10 and a tail stock assembly generally designated 12. To the left of the coil winding machine affixed to the same bed 14 is the wire dispensing mechanism of the present invention generally designated 16 which operates to feed wire to the coil winding machine in synchronization with the operation of the coil winding machines.

Although the coil winding machine is old and well known to those skilled in the art a brief description of the environment in which the wire dispensing mechanism of the invention operates is believed to be in order.

When a coil is finished it is cut from the supply wire adjacent the end of the coiling head and removed by a pickup mechanism none of which are shown. The cutting mechanism is so situated that a short length of wire extends from the end face 18 of the coiling head mechanism 20. The wire is held in this position by means of a clamping member 22 which is forced against the wire by the coaction between the break arm 24 and stop member 26. The tail stock operating mechanism 28 is then moved to the left toward the coiling head through operation of the crank arm 30 operating in response to a cam drive mechanism (not shown) similar to that illustrated in FIG. 3. A pair of gripping jaws in the end 32 of the tail stock operating mechanism 28 are impelled by springs 34 behind the tail stock and controlled by cams which cause the gripping jaws to open wide as they move toward the coil head. When these jaws are adjacent the coil head the jaws close and grip the projecting end of the filament for a sufficient length to form a filament leg to be used in the mounting of the filament within the lamps. During this operation disappearing type mandrel 36 has also been advancing until the mandrel has entered full depth into a fine center hold in the coiling head. At this point the coiling head begins to rotate and the drive mechanism simultaneously imparts motion to the arm 30 which slowly draws tail stock mechanism 28 away from the coiling head thus producing a wound coil about the mandrel

36 as it is withdrawn from the small hole in the center of the coiling head. When the desired number of turns have been made by the coiling head the coiling head stops. At this point the lever arm 30 in response to a sharp fall in the cam causes the tail stock mechanism to move rapidly away from the coil winding head 20 to form a straight filament length which when

cut in half forms the second leg of the coiled filament just completed and the lead leg for the next coil which will be gripped by the clamping jaws 32 at the beginning of the next coil winding cycle.

Spur gears 38 and 40, in conjunction with a drive mechanism (not shown), impart the rotational motion to the coiling head 20 in timed sequence with the reciprocal motion of the tail stock mechanism. As illustrated in FIG. 1 an adapter 42 has been added to facilitate the introduction of wire from the wire dispensing mechanism 16 into the coil winding mechanism or more particularly to the lathe portion 10 of the coil winding mechanism. This adapter replaces the prior art small 300 meter spool that was previously mounted at this point on the coil winding mechanism and rotated in that position coincident with the coiling head 20. In the past only a small spool could be employed because of the weight, the excessive torque imparted to the wire by the rotating coiling head and the stop and start movement imparted in jerking succession by the various gripping and pulling operations involved in coil winding operation.

The wire dispensing mechanism of the present invention eliminates each of these problems and permits wire to be mounted on the coiling machine directly on the 9,000 meter shipping spool upon which it is standard practice to ship wire from the wire drawing operation to the lamp coil manufacturing operation.

Referring now to the left-hand portion of FIG. 1 and more particularly to FIG. 2, the novel wire dispensing mechanism of the present invention will be described in detail. A 9,000 meter shipping spool 44 is mounted for rotation on an axle 46 between two parallel arms of a closed yoke 48. The yoke 48 is mounted for rotation by the shafts 50 which extends through bearings in end plates 52 of the carriage generally designated 54. The yoke 48 is rotatably driven through the left-hand shaft 50 by means of a variable speed DC motor 56 coupled thereto by coupling 58. The DC motor 56 is mounted on mounting plate 60 which is secured to the left-hand side of the carriage 54 by a bracket 62. The carriage 54 including the motor mounting plate 60 is mounted for reciprocal movement on a support plate 64 which is secured to the machine bed 14. The means for mounting the carriage 54 for reciprocal movement on the support plate 64 includes a pair of parallel rods 66 which extend through bearinged apertures 68 in the upstanding support members 52 of the carriage. The rods 66 are supported by upright members 70 on each end of the support plate 64.

A pivot support member 72 is mounted on the end of machine bed 14 at 73. Pivoted mounted at the other end of the pivot support member 72 is a bellcrank 74. One arm, 74a, of the bellcrank 74 extends from the pivot point to a pin and slot connection on the underside of the carriage 54. The other arm, 74b, of the bellcrank 74 carries a cam roller 78 which coacts with a rotatable cam 80. The cam 80 is mounted for rotation on the machine frame 14 and is driven by the same driving mechanism that drives the cam which operates lever arm 30. The rotatable cam 80 has an identical configuration to that of the cam which actuates the lever 30 and hence imparts substantially the identical motion to the carriage 54 as that which is imparted to the tail stock mechanism 28.

A spring 82 is attached to a projection on the machine base 14 at one end and at its other end is secured to the upstanding arm 74a of the bellcrank to urge the bellcrank in a clockwise direction as illustrated in FIG. 1 and hence forces cam roller 78 into continuous positive contact with the cam 80.

In operation, a shipping spool 44 is mounted on the closed yoke 48 by means of the axle 46 and hence will rotate in the direction indicated by the arrow X in FIG. 1 when wire is pulled therefrom. The variable speed DC motor imparts continuous rotation to the closed yoke 48 for a reason that will be later described. When the disappearing mandrel 36 is in its far left position in the fine center hole in the coiling head and the end of the wire gripped by the jaws 32, lever arm 30 starts to move to the right as the coiling head begins to rotate to form

the coil in response to operation of the drive gears 38 and 40. At this same time roller 78 is at the high point on the cam 80 causing the carriage 54 to be in its furthest toward-the-left position as is the mandrel 36. As the coil is wound the carriage 5 moves toward the lathe head portion end of the coil winder at the same speed as the tail stock mechanism 28 moves away from the coil head 20. This operation continues uniformly for about 270° of rotation of the cam 80 as well as its twin cam which drives lever arm 30. In a specific embodiment of this invention, for example that illustrated in FIG. 3, the fall is 0.406 inch in the first 270° of rotation of the cam 80. At this point the coil is wound and the coiling head is stopped and as described previously the tail stock mechanism 28 moves rapidly the distance of two coil leg lengths. The carriage also moves the same distance due to a complementary 0.406-inch fall in the next 20° of rotation of cam 80. Each of the cams then traverse a 10° dwell while the finished coil is being cut off from the wire supply and removed. The next motion imparted by the cam 80 and its complementary tail stock driving cam mechanism is caused by a 0.812-inch rise in the next 60° of cam rotation which drives the carriage and the tail stock rapidly back to their cycle starting position with the carriage all the way to the left and tail stock adjacent the face of the coil winding mechanism with the disappearing mandrel reinserted into the fine center hole in the coiling head face. As will be apparent, the contour of the cam causes the carriage to move one-half of its total distance in a first direction for the first 270° of cam rotation, the second half of its total distance 20 in a first direction for the next 20° of cam rotation, rest for the next 10° of cam rotation, and move its total distance in a second direction opposite to said first direction for the last 60° of cam rotation.

The reciprocal motion of the carriage 54 which is identical 35 with reciprocal motion of the tail stock mechanism 28 avoids an abrupt pulling or stopping of the wire as it proceeds through the coil winding process.

The speed at which the yoke 48 is continuously rotated is 40 slightly less than the rotational speed of the coiling head 20 and should be varied depending on the turns per inch of coil desired and the diameter of the wire. These parameters must be determined empirically with respect to the individual coil type and the size of the coil being wound. The principle involved in the rotating of the carriage yoke 48 in a continuous 45 fashion at slightly less than the rotational speed of the coiling head 20 is to permit continuous rotation of the yoke but still offer substantially total removal of the torque induced into the wire by the coiling head through an over torqueing of the wire in opposite directions as the process proceeds. Although the coiling head imparts a greater torque to the wire than that which is taken out during the actual coiling portion of the coil winding operation by rotating the closed yoke, the continuous rotation of the closed yoke during those periods when coil winding head 20 is not rotating over compensates and imparts a slight torque in the opposite direction which will then be taken out when the coiling head rotates again to form a coil. The net result is hence a flip-flop type torqueing of the wire as it is removed from the spool. This minimal amount of torqueing has no adverse effect on the final coiled filament. Of course, the rotatable mounting of the spool within the closed yoke 48 is necessary to permit the wire to be fed from the spool to the coil winding machine.

As will be apparent from the foregoing the wire dispensing 65 mechanism of the present invention provides a fully synchronized and automated mechanism for feeding filament wire to filament coil winding machines in which there is no abrupt changes in motion through pulling or clamping of the wire at the coiling head end which is not totally compensated 70 for by movement of the carriage. Furthermore, continuous rotation of the yoke eliminates the buildup of excessive torque on the filament wire which can and has changed optical and electrical characteristics of the completed lamp filament.

Since various changes may be made in the above described 75 apparatus without departing from the spirit thereof, it is in-

tended that all matter contained in the foregoing description and as shown in the accompanying drawings, shall be interpreted as illustrative and not in a limiting sense.

We claim:

1. In combination with a coil winding machine which continuously winds filament coils about a linearly reciprocable mandrel through a rotating coiling head mechanism, a filament wire dispensing mechanism comprising:

a base;

a carriage mounted for reciprocal motion on said base and having a pair of upright support members thereon;

yoke means mounted for rotation between said upright support members;

first drive means mounted on said carriage and connected to said yoke means for imparting continuous rotary motion to said yoke means;

a wire containing spool mounted on said yoke means for rotation about an axis perpendicular to the axis of rotation of said yoke; and

second drive means for imparting reciprocal motion to said carriage in timed relationship to the linear motion of the mandrel of said coiling-winding machine.

2. The wire dispensing mechanism according to claim 1, wherein a pair of parallel guide rods are mounted on said base and said carriage is journaled on said rods for sliding movement thereon.

3. The wire dispensing mechanism according to claim 2, wherein said yoke means has a closed rectangular configuration and two opposite sides thereof are mounted for rotation in said upright support members while the other two sides of said closed rectangular yoke have journaled therein the axle of said wire containing spool.

4. The wire dispensing mechanism according to claim 1, wherein said second drive means is a bellcrank connected at one end to said carriage and the other end having a cam roller which coacts with a continuously driven cam.

5. The wire dispensing mechanism according to claim 4, wherein the contour of said cam causes said carriage to move one-half of its total distance in a first direction for the first 270° of cam rotation, the second half of its total distance in

said first direction for the next 20° of cam rotation, rest for the next 10° of cam rotation, and move its total distance in a second direction opposite to said first direction for the last 60° of cam rotation.

5 6. In combination with a coil winding machine having a reciprocable mandrel and a coil winding head, which coil winding head winds a coil filament about the mandrel as the mandrel is withdrawn from the coil winding head; the improved filament wire dispensing mechanism which comprises:

a wire containing spool;

rotatable spool support means mounting said spool for rotation about the axis of said spool as wire is drawn therefrom;

first drive means for imparting continuous rotary motion to said rotatable spool support means;

a reciprocable carriage, said carriage having mounted thereon said rotatable spool support means and said first drive means; and

second drive means for imparting reciprocal motion to said carriage in timed relationship to the movement of said reciprocable mandrel of said coil winding machine.

20 7. A wire dispensing mechanism according to claim 6, wherein said carriage includes a pair of upright support members and said rotatable spool support means is a closed yoke mounted for rotation between said pair of upright support members about an axis parallel to the direction of reciprocal movement of said carriage.

8. A wire dispensing mechanism according to claim 7, wherein said second drive means includes a bellcrank having its first arm connected to said carriage and its second arm carrying a cam roller urged into contact with a continuously rotating cam.

30 9. The wire dispensing mechanism according to claim 8, wherein the contour of said cam causes said carriage to move one-half of its total distance in a first direction for the first 270° of cam rotation, the second half of its total distance in said first direction for the next 20° of cam rotation, rest for the next 10° of cam rotation, and move its total distance in a second direction opposite to said first direction for the last 60° of cam rotation.
